C. E. MORRIS.
PLATE FOR BOOTS AND SHOES.
APPLICATION FILED APR. 19, 1917.

1,255,911.

Patented Feb. 12, 1918.

UNITED STATES PATENT OFFICE.

CHARLES E. MORRIS, OF METALINE, WASHINGTON, ASSIGNOR OF ONE-HALF TO
CHARLES BOSLEY, OF METALINE, WASHINGTON.

PLATE FOR BOOTS AND SHOES.

1,255,911.

Specification of Letters Patent. Patented Feb. 12, 1918.

Application filed April 19, 1917. Serial No. 163,196.

To all whom it may concern:

Be it known that I, CHARLES E. MORRIS, a citizen of the United States, residing at Metaline, in the county of Pend Oreille and State of Washington, have invented certain new and useful Improvements in Plates for Boots and Shoes; and I do hereby declare the following to be a full, clear, and exact description of the invention, such as will enable others skilled in the art to which it appertains to make and use the same.

This invention relates to half sole and heel plates for boots, shoes and the like.

The object of this invention is to provide a metal plate for shoes particularly the style used by carpenters, shinglemen, lumbermen, woodsmen and all persons engaged in occupations where they are continually walking on smooth or slippery surfaces, and the object of this invention being to produce a shoe that will absolutely prevent the wearer from slipping or skidding in either direction and thus preventing him from being injured.

Another object of this invention is to provide a half sole and heel plate being formed or stamped from a piece of sheet steel to provide a plurality of depending calks or teeth, which are so constructed as to reinforce the portions from which they are stamped, and thus prevent the calks or teeth from being bent parallel with the body due to pressure placed thereon.

A further object of this invention is the provision of a device of this character, which will be simple, practical and comparatively inexpensive in construction, and which may be manufactured and sold at a low cost.

With these and other objects in view, the invention consists of the novel combination and arrangement of parts hereinafter more fully described and set forth in the claims hereto appended.

In the drawing:

Figure 1 is a bottom plan view illustrating the manner in which the plates are secured or attached thereto,

Fig. 2 is a side elevation of a shoe with the plates secured thereto,

Fig. 3 is a sectional view taken on the line 3—3 of Fig. 2,

Fig. 4 is a perspective view of the heel plate,

Fig. 5 is a sectional view taken through the plates to illustrate the manner in which

the calks are provided and their openings reinforced,

Fig. 6 is a sectional view taken on the line 6—6 of Fig. 5. 60

Like numerals of reference designate corresponding parts in all the figures of the drawings.

Referring more particularly to the drawing, the numeral 1 designates a shoe and 3 are the metal plates shaped to conform to 65 the shape of the heel and sole respectively of the shoe. Each plate is formed of suitable sheet steel or the like and has struck therefrom, the teeth 4, which teeth are bent downwardly at right angles to said plates and are substantially triangular and have their apexes constituting sharpened gripping points 5. The teeth are arranged transversely across the plates and each transverse 70 row of teeth are arranged at a spaced distance apart and the teeth are also formed near the side peripheral edges of each of the plates as at 6 to prevent the wearer from slipping in either direction. 75

The plates each are provided with the cut out portions 7, which are arranged between the rows of the teeth as shown, and these cut out portions reduce the amount of weight. 80

The teeth of each of the plates define a substantially V-shaped opening 8, the walls of which are bent downwardly at right angles as at 9 to reinforce the same. The side edges of the teeth curve rearwardly as 90 at 10 and the points slightly curve upwardly as at 11 to define substantially cup-shaped teeth, which reinforce and prevent the collapsing of the teeth, due to excess pressure placed thereon. 95

Each of the plates is provided adjacent its marginal peripheral edge with the spaced openings 12, which is adapted to receive suitable fastening means 13, such as screws or the like and thus detachably securing the 100 sole and heel plate respectively to the heel and sole of a shoe respectively.

The screws or the like 13 are inserted in the openings 12 and arranged at spaced relation around the peripheral edge of the 105 plates and adapted to be embedded in the sole and heel of the shoe respectively, thus rigidly securing the plates in position and preventing the surface of the sole or heel from being worn upon, during the wearing 110 of the shoe, it being understood that the calks of the plates or teeth of the plates

assume all of the pressure of the wear plates thereon and prevent skidding or sliding of the person in either direction.

In operation, the plates are stamped as described to provide the substantially triangular openings, thus providing the teeth, which depend from the under sides of the plates and at right angles thereto, the walls of the openings are bent downwardly at right angles to reinforce the same, the side edges of the teeth are curved rearwardly to provide the substantially cup-shaped teeth, which have the sharpened apexes 6, which prevent the skidding or sliding of the wearer of the shoe in either direction.

I claim:

1. A plate for soles and heels stamped of a sheet of metal to provide depending triangular shape teeth and the walls of the openings from which the teeth are struck being bent downwardly at right angles to the plate to reinforce the same, the side edges of the teeth curved rearwardly and their apexes curved upwardly to reinforce said teeth to provide shallow calks, and means for securing the plates to the sole and heel respectively, as and for the purpose specified.

2. A plate for the soles and heels of shoes, each plate formed or stamped from a single piece of sheet steel and shaped to conform to the configuration of the heel and sole respectively, each of the plates provided with spaced transversely arranged rows of teeth, which teeth are struck from the body of the plate and depend downwardly at right angles thereto, the walls of the openings defining the teeth curved downwardly and outwardly to reinforce the same and the

side edges of the teeth being curved rearwardly to reinforce and strengthen the teeth when applied to the heel and sole of the shoe, and means adjacent the periphery of the plates to facilitate the securing of the plates to the sole and heel of the shoe.

3. A plate for soles and heels comprising plates adapted to conform to the configuration of the sole and heel respectively, each of said plates formed of a sheet of steel and having struck therefrom a plurality of transversely arranged rows of substantially triangular teeth, said teeth being arranged at a spaced distance apart and each row at a relatively spaced distance apart, the teeth defining substantially triangular openings, the walls of which are bent downwardly at right angles to the plates, and curved forwardly to reinforce the openings defined by the teeth, the side edges of said teeth being curved rearwardly to form substantially shallow calks, which will reinforce and strengthen the teeth and prevent them from collapsing when under pressure, the apexes of said teeth curved outwardly to provide ground engaging portions, and said plates being each provided adjacent the marginal edges with spaced openings to receive fastening means to facilitate the securing of the plates to the heels and soles respectively.

In testimony whereof I affix my signature in presence of two witnesses:

CHARLES E. MORRIS.
